UNITED STATES PATENT OFFICE.

FRANK BLATCHFORD, OF BROOKLINE, MASSACHUSETTS, ASSIGNOR TO WRIGHT MANUFACTURING COMPANY, OF LAWRENCE, MASSACHUSETTS, A CORPORATION OF MASSACHUSETTS.

REINFORCING-STRIP FOR BUTTON-FLIES.

1,103,558.

Specification of Letters Patent. Patented July 14, 1914.

Application filed February 19, 1914. Serial No. 819,704.

To all whom it may concern:

Be it known that I, FRANK BLATCHFORD, a citizen of the United States, and resident of Brookline, in the county of Norfolk and 5 State of Massachusetts, have invented certain new and useful Improvements in Reinforcing-Strips for Button-Flies, of which the following is a specification.

This invention relates to means for reinforcing the fly in which the button holes of 10 a button shoe are formed, the object of the reinforcement being to strengthen the edge of the fly at the outer ends of the button holes and prevent said edge from being torn 15 by the strain exerted on it by the buttons engaged with the button holes.

The object of the invention is to provide a reinforcing strip having the requisite tensile strength and adapted to be stitched to the 20 inner side of a button hole fly and interposed between the fly and its lining and to conform accurately to the contour of the outer edge of the fly without adding appreciably to the thickness and stiffness of the 25 fly.

The invention consists in a reinforcing strip characterized as hereinafter described.

Of the accompanying drawings forming a part of this specification: Figure 1 represents an enlarged side view of a portion of a reinforcing strip embodying my invention; 30 Fig. 2 represents a view of the inner side of a portion of a button hole fly reinforced by said strip, a portion of the fly lining being broken away; Fig. 3 represents an enlarged 35 section on lines 3—3 of Fig. 2.

The same reference characters indicate the same or similar parts in all the views.

In carrying out my invention I form, 40 preferably by means of a braiding machine, a reinforcing strip of indeterminate length adapted to be cut up into pieces each adapted to reinforce a single button hole fly, said strip being adapted to be secured by a line of 45 stitches *a* to the body or outer portion *b* of a fly, and to be interposed between said portion and the lining or inner portion *c*, the outer edge of which is usually secured to the outer edge of the portion *b* by a line of 50 stitches *d*. The button holes *e* are formed as usual in the parts of the fly.

The reinforcing strip of my invention comprises a reinforcing portion composed of one or more longitudinal strands 12 (two of

which are here shown) of any suitable material which, without involving undesirable bulk or thickness of the completed strip, possesses a sufficient degree of tensile strength. Fibers of linen, cotton, or other material assembled to form a thread-like strand may be employed, or the strand may be made of fine copper or other wire. The strip also comprises an attaching portion 13 composed of fibrous threads 13^a of cotton or other suitable material, the threads 13^a being finer or thinner than the reinforcing strand or strands, when the reinforcing material is fibrous. The threads 13^a are interengaged with each other and with the reinforcing strand or strands, preferably by means of a 70 suitable braiding machine adapted to convert the threads 13^a into a flat braided fabric and engage them with the reinforcing strands as indicated by Fig. 1, the threads 13^a extending in zig-zag fashion as usual in 75 braided fabrics, while the reinforcing strands 12 extend from end to end of the completed fabric without lateral deviation.

The reinforcing strands are at one edge portion of the completed strip so that the 80 greater part of the attaching portion is at one side of the reinforcing portion and is adapted to overlap the part of the fly in which the outer ends of the button holes are formed. The cutter which forms the button 85 holes may therefore form notches in the inner edge of the attaching portion, and when the button holes are reinforced by the usual stitches the reinforcing stitches at the outer ends of the button holes attach the 90 margins of said notches to the fly. The strip attaching stitches *a* preferably engage the outer portion of the strip and may be formed between the strands 12 when two are 95 employed, as shown by Fig. 3.

The chief function of the attaching portion is, as its name implies, to receive the stitches *a* which attach the reinforcing portion to the fly, and its width need be no greater than is required to enable the reinforcing strip as a whole to be conveniently manipulated and applied to the fly, hence a relatively narrow strip which is flexible in all directions may be employed. The reinforcing strip constructed as described may 105 be made so thin and flexible that its presence in a fly does not objectionably increase either the thickness or the stiffness of the fly.

Having described my invention, I claim.

1. As an article of manufacture, a thin, flexible elongated reinforcing strip, comprising a reinforcing portion adapted to conform to a button hole fly between the outer margin thereof and the outer ends of the button holes, and composed of one or more longitudinal strands, and a textile attaching portion composed of threads interengaged with each other and with the strand or strands of the reinforcing portion and adapted to receive attaching stitches, the longitudinal strand or strands having greater tensile strength than the threads of the attaching portion.

2. As an article of manufacture, a thin, flexible elongated reinforcing strip, comprising a reinforcing portion adapted to conform to a button hole fly between the outer margin thereof and the outer ends of the button holes, and composed of one or more longitudinal strands, and a textile attaching portion composed of threads interengaged with each other and with the strand or strands of the reinforcing portion and adapted to receive attaching stitches, the longitudinal strand or strands having greater tensile strength than the threads of the attaching portion, said reinforcing portion being located at one edge of the strip, while the attaching portion constitutes the greater part of the width of the strip and forms a lip adapted to overlap the outer ends of the button holes and to be attached at intervals to the fly by the stitches which reinforce the outer ends of the button holes.

3. As an article of manufacture, a thin, flexible elongated reinforcing strip, comprising a reinforcing portion adapted to conform to a button hole fly between the outer margin thereof and the outer ends of the button holes, and composed of one or more strands extending without lateral deviation lengthwise of the strip, and a textile attaching portion composed of braided threads ex-

tending in a zig-zag direction, and engaging the longitudinal strand or strands, the latter being of greater tensile strength than the threads and located at one edge of the strip.

4. A button hole fly having a series of button holes and a thin, flexible elongated strip attached to the fly by stitches extending between the edge of the fly and the outer ends of the button holes, said strip including a reinforcing portion composed of one or more elongated, flexible, attenuated strands extending parallel with the edge of the fly outside the outer ends of the button holes, and a textile attaching portion engaging the attaching stitches and composed of threads inter-engaged with each other and with the strand or strands of the reinforcing portion.

5. A button hole fly having a series of button holes reinforced by the usual stitches, and a thin, flexible elongated strip attached to the fly by stitches extending between the edge of the fly and the outer ends of the button holes, said strip including a reinforcing portion composed of one or more elongated, flexible, attenuated strands extending parallel with the edge of the fly outside the outer ends of the button holes, and a textile portion engaging the attaching stitches and composed of threads inter-engaged with each other and with the strand or strands of the reinforcing portion and forming a lip the continuity of the inner edge of which is interrupted by notches coinciding with the outer ends of the button holes, the margins of said notches being secured to the fly by the usual reinforcing stitches at the outer ends of the button holes.

In testimony whereof I have affixed my signature, in presence of two witnesses.

FRANK BLATCHFORD.
